CLAIM

We claim the ornamental design for a food processing
attachment, as shown and described.

DESCRIPTION

FIG. 1 is a top perspective view of the food processing
attachment of the present invention;

FIG. 2 is bottom perspective view of the food processing
attachment of the present invention;

FIG. 3 is a first side elevation view of the food processing
attachment of the present invention;

FIG. 4 is a second side elevation view of the food processing
attachment of the present invention;

FIG. 5 is a third side elevation view of the food processing
attachment of the present invention;

FIG. 6 is a fourth side elevation view of the food processing
attachment of the present invention;

FIG. 7 is a top plan view of the food processing attachment
of the present invention; and,

FIG. 8 is a bottom plan view of the food processing attachment
of the present invention.

The broken lines in the figures are for contextual purposes
or show the environment and form no part of the claimed
design.
